FLUID PUMP

Charles F. Hautau, Huntington Woods, Mich., assignor, by mesne assignments, to Appliance Development Company, Oak Park, Mich., a corporation of Michigan

Application September 9, 1946, Serial No. 695,750

12 Claims. (Cl. 230—130)

1

This invention relates to fluid pumps and particularly to air pumps or fans of the kind employed with vacuum cleaners, although in its broadest aspects it relates to any fluid moving device.

An object of the invention is to generally improve air impellers, and to provide a device of that character which is simple in construction, economical to manufacture, and highly efficient in use.

Another object of the invention is the provision of an air impeller which is constructed and arranged in such manner that a greatly increased head is obtained without appreciable increase in the horsepower or motor speed, and with a resulting insignificant audible disturbance.

A further object of the invention is the provision of a fan constructed and arranged in such manner that the centrifugal forces generated in fans of conventional design are greatly minimized.

Another object of the invention is the provision of a fan having blades and supporting web made of an integrated stamping.

A further object of the invention is the provision of a fan constructed and arranged with blades having long curves, which collectively present a substantially continuous working surface adjacent the outside periphery, which tends to maintain the pressure, especially at low deliveries, with a minimum of air disturbance and leakage.

The applicant is aware of the fact that the art of centrifugal pumps, fans and compressors is highly developed. He also appreciates the fact that the performance of small high speed machines has been unpredictable, due to the influence of comparatively great leakage, and the effects of viscosity and the compressibility of the fluid on the flow.

Aircraft superchargers have been greatly refined but their application to domestic uses, such as for vacuum cleaners, is prohibitive because of the cost and weight factors. In the domestic fields the requirements of low cost and light weight have been met by the resort to the use of sheet metal construction, with large clearances between the fixed and moving members of the assembly.

Domestic vacuum cleaner fans are generally of the shrouded type, with radial flow, and consist of discs mounted to the drive shaft, the discs having vanes secured thereto to impart rotation to the fluid. The discs also employ a shroud or cover attached to the vanes on the opposite side of the disc, with a central hole for the entrance

2

of the fluid between the shroud and the disc. In those structures the shrouds support the vanes and prevent the fluid from escaping the action of the vanes by entering the large clearance between the fan and the housing. In such known structures the centrifugal forces developed by high speeds, make it extremely difficult to maintain the vanes in position.

The instant invention contemplates the making of the vanes integral with the driving disc, the shroud, or both by drawing projections in the sheet material of which they are formed. Such a process has great versatility in allowing the production of projections of any desired outline, which permits the designer great freedom in his choice of shape and contour for the vanes, all of which results in an inexpensive method of fabricating a device of the character indicated with the cost and weight factors reduced to a minimum.

The fabrication of the fan in the manner herein taught permits the assembly of a single stage fan from two accurately and uniformly matched pieces, which insures perfect balance at comparatively high speeds. It also lends itself to multiple stage applications wherein the fluid passes from the exterior of one fan to the entrance of the next.

The invention further contemplates the incorporation in multiple stage applications and integral with the shroud of the fan, or integral with that part of the interstage passageway adjacent to the following fan, of a short tubular portion which clears the adjacent member of the assembly radially by a smaller dimension than the axial clearance between the fixed and moving members. This reduces the clearance through which leakage might occur, and through proper design in multiple stage applications the leakage through radial clearances may be reduced to a minimum.

The foregoing and other objects and advantages of the invention will become more apparent as the description proceeds, reference being made from time to time to the accompanying drawings, forming part of the within disclosure, in which drawings:

Fig. 1 is a front elevational view of a fan embodying the invention.

Fig. 2 is a side elevational view thereof.

Fig. 3 is a fragmentary detail in perspective taken from the reverse side of Fig. 1.

Fig. 4 is an elevational view with parts broken away of a multiple stage fan assembly complete with housing and motor.

Referring now more particularly to the drawings, it will be understood that in the embodiment herein disclosed, my improved fan comprises a circular sheet of aluminum 7, or other suitable material, which is stamped with a plurality of comparatively deep recesses 8 which are substantially in the form of curved tear drops. The recesses 8 have inclined side walls 9 along their widest section, which side walls tend to approach the perpendicular as they skirt the narrow portion of the recesses, as at 10.

The recesses 8 are arranged in staggered relation around the face of the plate 7 (Fig. 1), so that the narrow portion of one recess overlies the wide portion of the adjacent recess. On the reverse side (Fig. 3) the side walls 11 and 12 of two adjacent recesses define narrow passageways 13, which terminate at the periphery.

The passageways 13 are further defined by a backing plate or shroud 14 of the same material and diameter as the plate 7. The shroud 14 is secured by spot welding the same flush to the backs of the recesses 8, as at 15. Except where the shroud 14 contacts the backs of the recesses 8, the plate 7 and the shroud 14 remain in spaced relation to define an air space substantially the depth of the recesses 8. The shroud 14 has a central opening 16 whereby the fan may be mounted on a shaft. The plate 7 has a cut-out portion 17 which serves as a port for incoming air. In operation, the fan is rotated in the direction indicated by the arrows in Fig. 1, the air enters the space defined between the plates 7 and shroud 14, through the cut-out portion 17, and moves radially where it is picked up by the inside walls of the recesses 8 and is discharged through the passages 13 to the periphery of the fan.

In a multiple stage fan, such as disclosed in Fig. 4, the air discharged from the periphery of a rotating fan is picked up at the periphery by a stationary member constructed in substantially the same manner as hereinabove described, and moves toward the center thereof where it is in turn picked up by another rotating fan and treated as hereinbefore described.

In Fig. 4 I show a plurality of fans, such as disclosed in Fig. 1, mounted on a shaft 18, which is provided with spacers 18A, of a motor 19 which is supported by roller bearings 20 and 21 carried in the housing 22. The reference characters 23 and 24 indicate brush-holders for the motor 19. A cover plate 25 is secured to the housing 22 by means of machine screws 26. The cover plate 25 has a central opening 27 through which air is drawn, as shown by the arrows Fig. 4. In this embodiment the first stage fan 28 is secured to the shaft 18 and rotates therewith. The fan 28 is constructed as shown in Fig. 1, and described hereinabove.

The stator 29 is constructed in the same manner as is the fan 28, except in this instance the backing plate or shroud 30 is secured to the cover plate 25 and remains stationary. The edge of the cut-out portion 31 of the stator 30 is bent inwardly and overhangs the edge of the cut-out portion 32 formed in the plate 33 comprising part of the second stage fan 34 which is secured thereto and adapted to rotate with the shaft 18.

The stator 35 is mounted to the housing 22, as at 36. The edge of the cut-out portion 31 of the stator 35 is bent inwardly so that there is again a minimum of clearance between the stator 35 and the third stage fan 38. This arrangement reduces to a minimum the possibility of air leakage and back pressure being built up.

The housing 22 is formed with a web 39 which serves as a stator for the air discharged from the periphery of the third stage fan 38. The air discharged from the third stage fan 38 passes through the housing cooling the motor 19, and is discharged through the end of the housing opposite the fans.

Although I have shown a three stage assembly, it will be understood that any number of stages may be employed by providing additional fans and stators for the required results.

A fan constructed as herein disclosed is very light in weight, is inexpensive to manufacture, and produces a very substantial head with a minimum of horsepower, and with a minimum of noise and air disturbance.

Having described my invention, what I claim and desire to secure by Letters Patent is:

1. A fan comprising a circular plate formed with a plurality of tear drop shape recesses formed therein, each of said recesses having inclined side walls along the widest section, the inclination of the side walls gradually being reduced as the width of the recess is reduced.

2. The structure defined in claim 1, in which the longitudinal walls of said recesses define long curves and said recesses are arranged in staggered relation, with the narrow portion of one recess overlying a substantial part of the wide portion of an adjacent recess, there being a comparatively narrow passageway defined between adjacent recesses.

3. The structure defined in claim 1, including a comparatively large centrally positioned cut-out portion adapted to serve as an air intake, and a backing plate or shroud integral with the backs of said recesses.

4. A fan comprising a pair of comparatively thin matched stampings secured in spaced relation by welding, one of said stampings being provided with a plurality of overlapping tear drop shape recesses along the periphery thereof, the adjacent recesses defining narrow passageways, and each recess having gradually inclined side-walls along the widest section thereof.

5. The structure defined in claim 4, in which said one of said stampings is provided with a large centrally disposed cut-out portion.

6. A fan comprising a pair of matched stampings, one of which is provided with a plurality of overlapping recesses, the adjacent walls of which recesses are progressively inclined and defined peripherally directed narrow air passageways.

7. A fan comprising a pair of thin matched plates, one of said plates having a plurality of overlapping arcuate recesses formed therein, said recesses comprising spacers between said plates, the walls of said recesses being progressively inclined and the walls of adjacent recesses defining narrow passageways terminating along the outer periphery of said plates.

8. The structure defined in claim 7, in which each plate is provided with a centrally positioned cut-out portion, the edges of the cut-out portion of one plate being bent axially, and extending into the cut-out portion of an adjacent plate.

9. In a device of the character described, the combination with a motor and a housing of a plurality of fans and stators, each fan and each stator comprising a pair of matched plates, one plate of each pair having a plurality of overlapping arcuate recesses formed therein, the walls of said recesses being progressively inclined and adjacent recesses defining narrow air passage-

ways terminating at the periphery of said plates.

10. The combination defined in claim 9, in which one plate of each pair is provided with a centrally positioned cut-out portion adapted to serve as an air passageway.

11. In a device of the character described, the combination with a motor and a housing of a plurality of rotors and stators arranged in co-operating relationship, said rotors being secured to the shaft of said motors, said stators being secured to said housing, each of said rotors and said stators consisting of a pair of matched plates, one plate of each pair having a plurality of overlapping arcuate recesses formed therein, the walls of said recesses being progressively inclined and the walls of adjacent recesses defining narrow air passageways terminating along the periphery of said plates.

12. The combination defined in claim 11, in which one of the plates of each stator is provided with a centrally positioned cut-out portion, the edges of which are bent axially and extend into the cut-out portion of an adjacent plate to define an air passageway.

CHARLES F. HAUTAU.
